(57) **CLAIM**

The ornamental design for an elastic strapping cord friction pad, as shown.

DESCRIPTION

FIG. 1 is a front isometric view of the elastic strapping cord friction pad of the present invention;

FIG. 2 is a front view of the invention of FIG. 1;

FIG. 3 is a back view of the invention of FIG. 1;

FIG. 4 is a top plan view in elevation of the invention of FIG. 1;

FIG. 5 is a bottom plan view of the invention of FIG. 1;

FIG. 6 is an enlarged side view of the invention of FIG. 1, as seen from the left side of FIG. 2; and,

FIG. 7 is an enlarged side view of the invention of FIG. 1, as seen from the right side of FIG. 2.
